United States Patent Office

Des. 188,622
Patented Aug. 16, 1960

188,622

LIGHTER OR SIMILAR ARTICLE

Seymour Rappoport, New York, N.Y., assignor to Ronson Corporation, Woodbridge, N.J., a corporation of
New Jersey

Filed Sept. 24, 1959, Ser. No. 57,673

Term of patent 14 years

(Cl. D48—27)

Fig. 1.

Fig. 2.

Fig. 3.

Fig. 4.

Figs. 1, 2 and 3 are respectively a side elevation, an end elevation looking from the right of Fig. 1, and a top plan view of a lighter or similar article embodying my new design; and

Fig. 4 is a perspective view thereof.

I claim:

The ornamental design for a lighter or similar article, substantially as shown.
